FINGER RING

Herman Gutknecht, Montreal, Quebec, Canada,
assignor to Henry Birks & Sons Limited, Montreal, Quebec, Canada

Application July 11, 1935, Serial No. 30,806

3 Claims. (Cl. 63—15)

This invention relates to improvements in finger rings equipped with settings of either the signet or jewel type and applies particularly to rings adapted to be worn on the little finger.

5 The main setting of the conventional ring is usually centered so that the weight of the ring is equally distributed at opposite sides of a vertical plane passing through the center of the ring. When worn on the little finger a ring 10 of this type is frequently displaced to a position where the setting lies at the outer side of the finger and is frequently damaged by contact with other objects. This accidental displacement of the setting towards the outer side of the little 15 finger is prevented in accordance with the present invention by designing the ring so that the weight is unequally distributed at opposite sides of the vertical center line, the heavier side of the ring being that which is fitted between the little finger and the next adjacent finger and being effective to prevent displacement of the setting toward the outer side of the little finger. To this end the ring provided in accordance with the present invention is designed so that the 20 major portion of the setting lies between the vertical center line and that side of the band portion of the ring which is fitted between the previously mentioned fingers.

Another feature of the invention consists in 25 flattening the heavier or inner side of the ring so that it may be worn with greater comfort and will not exert painful pressure on either the little finger or the next adjacent finger when these two fingers are squeezed together as in the act 30 of hand shaking.

The location of the setting so that its major portion lies between the vertical center line and the inner side of the band portion of the ring is of further advantage in that it enables a ring 35 of exceptionally attractive appearance to be achieved by applying all of the ornamentation to the band portion of the ring at the outer side of the setting instead of following the usual practice of ornamenting the band portion at opposite 40 sides of the setting.

Proceeding now to a more detailed description of the invention reference will be had to the accompanying drawing in which—

50 Fig. 1 is a top plan view of a ring designed in accordance with this invention.

Fig. 2 is a view in elevation looking toward the inner or heavier side of the ring.

Fig. 3 is a view similar to Fig. 2 but looking 55 toward the outer or lighter side of the ring.

Fig. 4 is a view in elevation looking in the direction of the ring opening.

Fig. 5 is a view similar to Fig. 4 but showing a slight modification.

Fig. 6 is a view looking toward the outer side 5 of the ring appearing in Fig. 5.

The ring shown in Figs. 1 to 4 inclusive comprises a band portion 5 equipped with an integral setting 6 of the seal or signet type. It will be observed that the setting 6 is offset with reference to a vertical plane P passing through the center of the ring so that the major portion of the setting lies between this plane P and the inner side 5a of the band 5. It will also be observed that the ring is shaped to present a flat 15 surface 7 extending from the horizontal axis of the ring to the top of the setting 6.

When the ring is worn on the little finger, as shown in Fig. 1, the flat surface 7 fits comfortably against the adjacent finger and serves to prevent inward turning movement of the ring. The flat surface 7 is preferably made of sufficient area so that, when the fingers are pressed together as in the act of hand shaking, it will not exert painful pressure against the finger with which it is in contact.

Since the ring described herein is heavier at the inner than at the outer side, due to the offset position of the setting 6, it is not so apt to turn outwardly on the little finger as an ordinary ring in which the center of the setting coincides with the vertical center line of the finger encircling band.

Since the outer side 6a of the setting 6 is set inwardly a considerable distance with respect to a vertical plane P' passing through the outer side 5b of the band 5, it will be appreciated that considerably more than the usual amount of space is available at the outer side of the setting for the placing of ornamentation 8 where it will be exposed to view when the ring is on the hand.

In Figs. 5 and 6 I have shown a slight modification in which the setting 10 is of the jewel type, and is arranged with its inner and outer sides offset inwardly with respect to parallel planes P² and P³ passing through the inner and outer sides of the band portion of the ring, it being noted, however, that the major portion of the setting is located between the plane P² and the vertical center line of the ring, which is represented by the plane P. As will be evident from Figs. 5 and 6 it is not absolutely necessary to design the ring so that the inner sides of the finger encircling band and the setting are merged into the flat surface indicated at 7 in Fig. 1.

In connection with the showing of Fig. 4 it will be understood that the portion indicated at 6 may be taken to represent merely the base on which a jewel or other ornament is mounted to form the 5 main setting.

Having thus described my invention what I claim is:—

1. A finger ring equipped with a setting which is offset so that, in the normal position of the 10 ring, the setting lies in a horizontal plane at the top of the finger encircling band with the major portion of the setting located at one side of a vertical plane containing the axis of the finger receiving aperture.

15 2. A finger ring equipped with a setting which is offset so that, in the normal position of the ring, the base of the setting lies in a horizontal plane at the top of the finger encircling band and

is positioned so that the major portion of the setting lies at one side of a vertical plane containing the axis of the finger receiving opening, said ring being further characterized in that the side of the finger encircling band toward which the setting is offset is formed to present a flat surface extending from the horizontal plane of the axis of the ring to the top of the setting, the plane of said surface being substantially parallel 5 with the aforesaid vertical plane.

3. A finger ring as set forth in claim 2, in which the side of the setting remote from the flat surface of the finger encircling band lies in a vertical plane between the opposite side of the band and the vertical plane containing the axis 10 of the finger receiving aperture.

HERMAN GUTKNECHT.
